HAIR CURLING DEVICE

Samuel Freeman, New York, N. Y., assignor to
William Finkelstein, New York, N. Y.

Application July 15, 1938, Serial No. 219,363

7 Claims. (Cl. 132—33)

My invention relates to a new and improved hair curler.

One of the objects of the invention is to provide a curler having parts which can be assembled at very low cost.

Another object of the invention is to provide a curler whose main parts can be made from moldable material, such as a cellulose acetate plastic or other thermoplastic material. The invention includes the use of artificial resins of various kinds such as Bakelite, etc.

Another object of the invention is to provide a device consisting of a minimum number of parts and which will be of durable construction.

Other objects of the invention will be set forth in the following description and drawing which illustrate preferred embodiments thereof, it being understood that the above statement of the objects of my invention is intended generally to explain the same without limiting it in any manner.

Fig. 1 is a perspective view of the improved device.

Fig. 2 is a longitudinal section through the central axis of the device.

Fig. 3 is a sectional view on the line 3—3 of Fig. 2.

Fig. 4 is a perspective view of the turnable member of the device.

Fig. 5 is a perspective view of the clamping member of the device.

Fig. 6 is a perspective view of the body of the device.

Fig. 7 is a perspective view of the cap member, which is applied to the member shown in Fig. 4.

Fig. 8 is a partial central longitudinal section of a modification, showing an insert in the turnable member to hold the bobby pin more securely.

Fig. 9 is a detail sectional view of the insert.

The device comprises a body member having a shank 1, which is integral with a sleeve 2. This body member can be molded from any suitable non-metallic material. All the parts can be made of metal if desired, as the invention is not limited to the use of any particular material.

The turnable member 3 is also preferably made of metal or of any suitable moldable material such as cellulose acetate plastic or the like.

As shown in Fig. 2, the front or free end of the turnable member 3 is provided with a longitudinal recess 3a. The axis of the recess 3a coincides with the longitudinal axis of the member 3. As shown in Fig. 4, the recess 3a can have a front tapered portion, and a rear portion of substantially cylindrical contour. Intermediate its ends 55 the member 3 is provided with an integral chan-

neled collar 4, having a shoulder 4a. The rear end of the member 3 is imperforate so as to provide an integral cap member 7. The member 3 is provided with a longitudinal recess 6, which registers with the longitudinal channel of the collar 4.

The channel of the collar 4 is preferably of the same width as the recess 6.

As shown in Fig. 4, the member 3 is thus provided with a longitudinal recess which extends 10 from the front lateral face of the cap member 7 almost to the front lateral face 4b of the collar 4. The collar 4 is provided with lateral bores 5.

A cap member 8 is also made of suitable resilient material which may be metal, cellulose acetate 15 plastic or the like. This member 8 has a hollow shank 9 which is integral with a head 10. The shank 9 is provided with a longitudinal channel.

When the parts are assembled as shown in Figs. 1 and 2, the longitudinal channel of the shank 20 9 registers with the recess 6.

The parts of the device can be sold as separate units to be assembled by the user. If the parts are assembled at the factory, the cap member 8 can be connected to the turnable member 3 by 25 suitable adhesive or by suitable mechanical connecting means. When the parts of the device are assembled, there is sufficient clearance or space inbetween them to insure easy turning of the member 3 in the sleeve 2.

The clamping bar 11 which is shown in Fig. 5 is preferably made of resilient metal or other resilient material. This bar 11 is provided with a pair of depending perforated lugs 12.

As shown in Fig. 3, a pivot pin 14 has its ends 35 located in the bores 5 of the collar 4, and said pivot pin 14 passes through the perforations of the lugs 12. The clamping bar 11 is thus pivotally connected to the separated walls of the collar 4 of the member 3.

As shown in Figs. 2 and 3, a spring 16 has its lower end located in a recess which is provided in the bottom wall of the recess 6. The upper end of said spring abuts the rear end-portion 17 of the clamping bar 11.

As shown in Fig. 2, the end-portion 17 is provided with an integral depending boss 18, which serves to center the spring 16.

The drawing is substantially to scale and reference can be made thereto for further details.

The spring 16 normally maintains the clamping bar 11 in the full-line position shown in Fig. 2. Upon downwardly pressing the end-portion 17 against the force of the spring 16, the clamp- 55

ing bar 11 can be turned to the broken-line position illustrated in Fig. 2.

After the members 3 and 11 have been assembled, the rear end-portion of the member 3 can be pushed through the sleeve 2, while the end-portion 17 is depressed and the bar 11 is held in the broken-line position shown in Fig. 2.

In the full-line position of member 11 which is shown in Fig. 2, the member 17 would be too high to permit the same to be pushed through the sleeve 2. The member 11 has a relatively depressed portion 17a between its clamping body and the end-portion 11. This depressed portion 17a is reinforced by a stamped-out rib.

15 The bore of sleeve 2 is wider at its front end than at its rear end, so as to provide a shoulder S. This provides a clearance at the front end of sleeve 2. This clearance and the recess 8 and the cut-out shape of collar 4 make it possible to 20 turn member 11 from the full-line to the broken-line position.

The sleeve 2 serves as a bearing in which the member 3 can be turned about its longitudinal axis.

25 After the members 3 and 11 have been thus assembled with the body of the device, the member 8 is moved into and secured in the position shown in Fig. 2, thus preventing any substantial left-hand movement of the member 3 relative to 30 the body of the device, because the end wall of the shank 9 then substantially abuts the rear lateral wall of the shank 1, leaving enough clearance for easy turning.

When the parts are assembled, the rear or 35 right-hand lateral end-wall of the collar 4 abuts the shoulder S which is provided in the interior of the sleeve 2, to limit the movement of member 3 relative to the body in the right-hand direction. A hair pin or bobby pin H can be inserted in the 40 position shown in Figs. 1 and 2 so that one of the shanks of said hair pin is held releasably within the recess 1a of the member 1 and the other shank is located in recess 3a.

The hair pin H can be readily pulled out of 45 the curler.

The shanks of the resilient metal bobby pin H are moved apart from their normal positions, in order to insert said shanks into the device, in the 50 position shown in Fig. 2. Hence, when the bobby pin is in said position, it is retained, in the curler by the resilience of said shanks. One end of the lock of hair is clamped between the member 3 and the member 11, after the shanks of the bobby pin have been inserted into recesses 1a and 3a. 55 The member 3 is then turned, without turning the hair pin, so as to wind the lock of hair spirally or helically around the member 3.

The clamping member 11 is then moved to the broken-line position shown in Fig. 2, so as to release the curl, and the curl is then pushed longitudinally into the broken-line end-position shown in Fig. 1, so that one of the shanks of the hair pin enters said curl and the other shank remains external to the curl. The curl and the hair pin are then removed from the device, so that the resilient shanks of the hair pin clamp the curl, so that the device can then be used with another hair pin for making another curl.

Fig. 9 shows an insert 25 having a collar 26 70 which may be made of metal or any other suitable material. A ferrule 27 is assembled with the collar 26, so that the ferrule 27 can be turned freely relative to the collar 26. The ferrule 27 has a head 28 whose diameter is greater than 75 the internal diameter of the collar 26 and which

is less than the external diameter of the collar 26. The ferrule 27 is provided with a through-and-through bore which also extends through the head 28. The collar 26 has a drive-fit in the enlargement 3b of the recess 3a, which is shown 5 in Fig. 8. Therefore the collar 26 and the member 27 can be assembled and the collar 26 can be forced into the recess 3b, until the front end of the collar 26 is flush with the front end of the member 3. The length of the recess 3b is 10 greater than the length of the ferrule 27, so that there is a clearance between the head 28 and the inner lateral wall of the recess 3b.

The axis of the bore 29 coincides with the axis of the recess 3a. The shank of the bobby pin 15 is passed through the bore 29 to enter the recess 3a.

The tip of the shank may abut the inner lateral wall of the recess 3a. The lateral diameter of the recess 3a is greater than the lateral diameter of the bore 29. This construction causes the resilient shank of the hair pin to be bent temporarily out of its normal shape when said shank is thus inserted through the bore 29 into the recess 3a. This aids in preventing said shank 25 from springing out of the member 3, when said member 3 is turned relative to the bobby pin and to the body of the device. When the member 3 is turned, the collar 26 turns in unison therewith, but the ferrule 27 does not turn. In the 30 embodiment shown in Fig. 4, the tapered shape of the front end of recess 3a also causes the resilient metal shank of the hair pin to be bent temporarily out of normal shape, when the shank of the hair pin is pushed into the cylindrical 35 inner part of recess 3a. This acts to prevent the hair pin from springing out of the device, when member 3 is turned relative to the hair pin. The shank of the hair fits fairly snugly in the rear portion of shank 3a, in Fig. 4. If the 40 diameter of the shank is one-sixteenth ($\frac{1}{16}$) of an inch, the cylindrical portion of recess 3a may have a diameter of five sixty-fourths ($\frac{5}{64}$) of an inch.

While I have shown a preferred embodiment 45 of the invention, numerous and very substantial changes can be made without departing from its spirit.

Likewise the invention covers numerous valuable sub-combinations which are not operative 50 per se and which can be used in many different forms of curlers.

It will be noted that the construction above specified makes it possible to apply the turnable member 3 and the clamping member 11 as a 55 sub-unit to the body of the device, and to remove the members 3 and 11 as a sub-unit from said body.

I claim:

1. A hair curling device comprising a body having a shank, the front end-wall of said shank having a longitudinal recess, said shank having a laterally offset bearing-sleeve, said bearing-sleeve, having an internal shoulder, a turnable member having a collar intermediate the ends 65 thereof, the rear end-wall of said collar substantially abutting said internal shoulder, said turnable member being turnable in said bearing, a clamping bar pivotally connected to the collar of the turnable member, said clamping-bar 70 having a portion thereof located within said bearing-sleeve and also having a portion extending rearwardly of said bearing-sleeve and having a portion extending forwardly of said bearing-sleeve, said turnable member having a recess in 75

which the adjacent part of said clamping bar is movable, a spring located in said recess and adapted to maintain the clamping bar in normal clamping position relative to said turnable member, a cap mounted on said turnable member and having a longitudinal channel which registers with the recess of said turnable member, said cap having its front end-wall substantially abutting the rear end-wall of the shank, the front 10 end-wall of said turnable member having a longitudinal recess therein.

2. A hair curling device comprising a body having a shank, said shank having a laterally offset bearing-sleeve, a turnable member turnably mounted in said bearing sleeve, a clamping bar pivotally connected to said turnable member, said clamping bar extending through said bearing-sleeve and having an exposed finger-portion, and a spring located intermediate a portion of 15 said clamping bar and a portion of said turnable member and effective to hold said clamping bar in normal clamping relation relative to said turnable member.

3. In a hair curling device, a turnable member having a recess extending inwardly from the front lateral face of said turnable member, said recess having a front portion of tapered shape and having a rear-portion of substantially cylindrical shape, the widest portion of said recess 20 being at the end face of said turnable member.

4. In a hair curling device, a turnable member having a first recess extending inwardly from the front end-face of said turnable member, a second recess of smaller diameter than the first recess and extending inwardly from the rear face of said first recess, said recesses having substantially the same longitudinal axis, a ferrule held turnably in said first recess so that the turnable member can turn relative to said ferrule, said 25 ferrule having a bore whose longitudinal axis is

substantially coincident with the common longitudinal axes of said recesses.

5. A device according to claim 4 in which the diameter of said bore is smaller than the diameter of the second recess.

6. A hair-curling device comprising a body-member having a laterally-offset bearing-sleeve, a turnable member having a bearing-portion thereof turnably mounted in said bearing-sleeve, a clamping bar pivotally connected to said turnable member, said clamping bar having a finger-portion whereby said clamping bar can be turned relative to said turnable member, said finger-portion being spaced longitudinally relative to said bearing-sleeve, and means independent of 10 the clamping bar and of the finger-portion thereof and adapted to hold the turnable member against longitudinal movement relative to said sleeve, the turnable member and said clamping bar being a sub-assembly which is independent 15 of said bearing-sleeve, said bearing-portion of the turnable member being independent of said clamping bar.

7. A hair-curling device comprising a body having a shank, said shank having a laterally-offset bearing sleeve, a turnable member, a clamping bar pivotally connected to said turnable member, said turnable member having an enlarged bearing-portion thereof located within said bearing-sleeve and fitting snugly but turnably against the adjacent part of the inner wall of said bearing-sleeve, said clamping bar having an exposed finger piece which is spaced longitudinally of said bearing-sleeve, additional means supplemental to 20 said turnable member and said clamping bar and adapted to hold the turnable member against longitudinal movement relative to the bearing-sleeve, said bearing-portion of the turnable member being independent of said clamping bar.

SAMUEL FREEMAN. 40
